attorney.

UNITED STATES PATENT OFFICE.

ALBERT MADEN, OF WATERFOOT, ENGLAND.

PROFILE TEMPLATE.

Application filed February 25, 1922. Serial No. 539,315.

To all whom it may concern:

Be it known that I, ALBERT MADEN, a subject of the King of Great Britain, residing at Ivy Cottage, 14 Turnpike, Newchurch, Waterfoot, in the county of Lancaster, in England, have invented a new and useful Improved Profile Template, of which the following is a specification.

This invention relates to an improved clamp or holder adapted to form or profile templates, and has for its object to provide a simple and efficient means for rigidly supporting a number of wires, rods, reeds or needles of equal dimensions in a parallel position.

Another object of my invention is to provide a clamp or holder whereby the wires or the like may be easily set to any desired contour.

20 A still further object of my invention is to provide the clamp or holder with a detachable handle which may be disconnected when not in use.

In my invention I provide a number of wires, rods, reeds or needles, composed of metal or any other suitable substance which slide longitudinally between guides for setting the wires, rods, reeds or needles to any desired shape, said wires and guides are 25 interposed with two elongated shaped plates or clamps having apertures near their respective ends for receiving two hollow studs which are screwed into the back or hinder plate, each stud having a rectangular shaped 30 distance piece thereon said distance pieces mounted between the clamps.

Suitable tubular bars are connected across the wires, rods, reeds or needles and are secured to the distance pieces by means of 40 rivets or screws for the purpose of supporting the wires, rods, reeds or needles in a parallel position.

The aforesaid clamps are lined on their inner faces with rubber or leather having a 45 corrugated facing for the purpose of giving an increased frictional hold.

50 Detachable handles provided with a circumferential groove are inserted into the aforesaid studs and rigidly secured thereto by means of the said groove engaging with a ball catch attached to a set screw provided with a spiral spring, and said set screw passing through the hinder plate and hollow stud respectively.

55 The above described handles project out

on either side of the clamps to enable the operator to hold my device.

The aforesaid hollow studs have a male thread at their upper ends which said ends extend to a suitable distance out from the front plate, and in turn receives a spiral spring and locking nut, the latter being screwed thereon after the wires or the like have been set thereby compressing the spiral springs into a recess provided in the outer side of the front clamp for the purpose of holding the wires or the like in position.

In the accompanying drawings, Fig. 1, is a front view of my device; Fig. 2, is a section on line A, B, in Fig. 1; Fig. 3, is a detail of the handle and ball catch, and Fig. 4, is a detail section of the clamp and corrugated material.

My invention comprises a series of wires a or the like, which may be set to any desired form from a drawing or article of which the contour is required in forming a template, said wires a being actuated between lateral guide bars b and are secured in a parallel position by means of clamps c, 75 and d, set on each side as hereinafter described.

The clamps c, and d, are secured together by means of hollow studs e, with distance piece f thereon and interposed therebetween. 85

Two tubular bars g, and g', are riveted or screwed at h to the plates f on each side of the clamps c, and d, for holding the wires a in their proper alignment.

The hollow studs e screw into the back or hinder plate c, and project out from the front clamp d, and in turn receive a spiral spring i and locking nut j, for the purpose of securing the wires a in their pre-arranged 90 positions.

The detachable handles k having a circumferential groove l are inserted into the aforesaid hollow studs e and extend outwardly from each clamp c, and d, said handles being held by means of a ball catch m 100 integral with a set screw n having a spiral spring o thereon, said screw n passing through the hinder plate c thereby causing the said catch m to engage in the groove l.

The aforesaid clamps c, and d, have a recess p as shown in Fig. 4, on their inner faces for receiving a rubber pad q having a corrugated face r for the purposes as hereinbefore described.

I claim:

110

In a conformator gage, two clamp plates comprising a front plate and a hinder plate, each having a rubber pad on its inner side, there being an aperture adjacent each end 5 of each plate guide bars passing between said plates at the respective ends thereof, a series of wires adapted to move laterally between said plates and guided by said bars, studs screwed into the apertures in said 10 hinder plate and projecting through the corresponding apertures in the front plate, distance pieces interposed between said plates and surrounding said studs and adapted to contact said guide bars, thumb nuts on said studs adapted to force said 15 clamps together and springs respectively interposed between each nut and the front plate, detachable handles inserted into longitudinal bores in said studs and adapted to extend outwardly from said clamp plates, 20 and catch means carried by said hinder plate adapted to engage in circumferential grooves in said handles respectively and to hold the same removably secured in said studs.

ALBERT MADEN.
